UNITED STATES PATENT OFFICE.

MAX N. AARON, OF PHILADELPHIA, PENNSYLVANIA, ASSIGNOR TO FRIEDBERGER-AARON MANUFACTURING COMPANY, OF PHILADELPHIA, PENNSYLVANIA, A CORPORATION OF PENNSYLVANIA.

DESIGN FOR TRIMMING.

51,164.

Specification for Design.

Patented Aug. 21, 1917.

Application filed June 6, 1917. Serial No. 173,247. Term of patent 3½ years.

To all whom it may concern:

Be it known that I, MAX N. AARON, a citizen of the United States, residing in Philadelphia, county of Philadelphia, and State of Pennsylvania, have invented a new, original, and ornamental Design for Trimming, of which the following is a specification, reference being had to the accompanying drawing, which forms a part thereof.

The trimming is adapted and intended to be cut into appropriate lengths and used as shoulder straps for ladies' underwear.

The figure is a plan view of a number of repeats of a trimming embodying my design.

The design comprises a longitudinally extending central strip *a* composed of rela-

tively fine thread comparatively closely knit with what is known in the art as a nubia stitch, a distinctive border *b* along each edge composed mainly of relatively coarse threads, and relatively fine and inconspicuous transverse threads *c* uniting the central strip and borders.

I claim—

The ornamental design for trimming, as shown and described.

In testimony of which invention, I have hereunto set my hand, at Philadelphia, on this 4th day of June, A. D. 1917.

MAX N. AARON.
